SHINGLE

Otto J. Kuhn, Syracuse, N. Y.

Application June 28, 1940, Serial No. 342,991

5 Claims. (Cl. 108—7)

This invention relates to improvements in an asphaltum or equivalent pliable shingle and to the method of laying such shingles so as to form a weatherproof roofing or siding construction.

The shingles comprising this invention are preferably fabricated from pliable sheet material of a fibrous nature and which has been treated with bituminous and other material to render the same weather resistant. The shingles are laid in successive courses with the contiguous ends of the shingles of each course arranged in overlapping relation in what is known as the Dutch lap method.

The primary object of this invention is to provide an improved form or pattern of shingle whereby the same may be economically constructed and laid. In carrying out this object, I have provided each shingle with a holding means preferably formed integral therewith adapted to cooperate with the adjacent shingle of the same course for securing the exposed corner of the shingle in position, thereby permitting the use of relatively large shingles which greatly expedite the task of laying the shingles.

Another object of the invention is to provide a shingle having means for interlocking the same with an adjacent shingle of the same course so as to constitute a continuous exposed surface adapted to withstand the action of the elements thereon and particularly to prevent the exposed edge of each shingle from warping upwardly or from being lifted by the wind.

A further object of the invention resides in constructing shingles which, when laid in courses, provide a well defined shadow line formed by the exposed lower edges of the shingles and which extend from one end to the other of each row and add much to the pleasing appearance of the roof or other covering structure.

Other objects and advantages relating to the specific form of the shingle and to the method of laying the same will more fully appear from the following description taken in conjunction with the accompanying drawing, in which:

Figure 1 is a plan view of a shingle embodying the various features of this invention.

Figure 2 shows a portion of a roof or siding covered with the shingles of my invention.

Figure 3 is a perspective view on an enlarged scale, showing portions of the adjacent shingles of the same course and the locking means formed integral therewith which cooperate for securing the exposed corner of the upper shingle in position.

Figure 4 is a plan view of a portion of a sheet of roofing material showing the manner of cutting the shingles therefrom.

Figure 5 is a plan view of one end portion of a modified form of shingle illustrating the same as it is cut from a sheet of asphaltum or other suitable material.

Figure 6 is a perspective view illustrating a modified form of fastening means for interlocking the exposed lower corner of a shingle with an adjacent shingle of the same course.

Figure 7 is a detail longitudinal sectional view illustrating the manner in which the fastening means shown in Figure 6 is utilized for securing the lower exposed corner of one shingle with the adjacent portion of an underlying shingle of the same course.

Figure 8 is a perspective view showing the lower edge of a shingle of still further modified structure.

As shown more clearly in Figure 1 of the drawing, the main body 10 of each shingle is flat and made in the form of a trapezoid having its opposite longitudinal sides or edges 11 and 12 substantially parallel with each other. The opposite end edges 13 and 14 of the shingle are disposed at an angle to each other, one of the end edges, as 13, being straight and disposed at substantially right angles to the longitudinal center of the shingle and, therefore, to the opposite longitudinal edges 11 and 12. The other end edge, as 14, has relatively short portions 15 and 15' thereof adjacent the sides 11 and 12, respectively, formed straight and disposed at substantially right angles to the longitudinal center of the shingle and, therefore, to sides 11 and 12.

The upper edge or side 11 of the shingle is appreciably shorter than the lower edge or side 12 so that the end portions 15 and 15' are offset from each other longitudinally of the shingle. The major portion of the intermediate or central portion 16 of the end 14 is disposed at substantially right angles to the longitudinal center of the shingle but offset intermediate the end portions 15 and 15'. This central portion 16 of the end 14 may, as illustrated in Figure 1, be provided with stepped portions 16' providing convenient guides by which the amount of overlap of the shingles of one course with respect to the shingles of the next preceding course may be readily determined.

The upper and lower ends of the intermediate portion 16 of the end 14 are connected with the end portions 15 and 15', respectively, by arcuate edges or surfaces 17 and 17'. The edge or sur-

face 17 is preferably a convex surface so as to provide the shingle with ample surface adjacent thereto for receiving a fastening nail or the like by which the corresponding portion of the shingle may be secured to the underlying supporting surface of the roofing or siding structure. The arcuate or curved surface 17' at the lower side of the shingle is complementary to the surface 17 so as to not only facilitate the cutting of the shingle but also provide for a minimum amount of waste and is, therefore, a concave surface.

It will be understood by referring more particularly to Figure 4 that the length of the portions 15 and 15' of end 14 are substantially equal and are only of such a length as to give the portion of the shingle immediately adjacent the end 15' enough strength to support the same before the shingle is laid and also to give it sufficient body or width to prevent water from readily flowing in under the adjacent portion of a second shingle overlying the end portion 14, as will hereinafter be more clearly understood.

As hereinbefore stated, the upper edge or side 11 of the shingle is of shorter length than the lower side or edge 12. In this instance, the upper side 11 is substantially two-thirds the length of the side 12 and is provided with an extension 19 equal in length to substantially one-half the length of the upper side 11 of the shingle. The extension 19 is arranged adjacent the end 14 of the shingle and has the forward or outer end 19' thereof arranged coincident or flush with the end portion 15.

The lower side 12 of the shingle is provided with a recess 21 complementary to the extension 19. In other words, the recess 21 is arranged substantially midway between opposite ends of the side 12 and has a length substantially equal to one-third of the length of the lower edge so that the shingle may be said to be provided with extensions 22 and 23 arranged at opposite ends of the recess 21, each of said extensions 22 and 23 being of substantially the same length as said recess. The extension, as 22, disposed adjacent the end 13 of the shingle is provided with a holding tab or flap 25 formed entirely within the body of the shingle by a slit 26 extending inwardly from the lower edge of the extension 22 in angular relation thereto, as shown in Figure 1. The upper or inner end of the slit 26 terminates in a lateral portion 26' which extends substantially parallel with the lower edge of the portion 22 and terminates at a hole or eyelet 27 provided in the shingle intermediate the upper or inner end of the major portion of the slit 26 and the end 13 of the shingle.

The extension portion 23 adjacent the end 14 of the body of the shingle is provided with an inwardly extending slot 29 which is of substantially the same length as the distance the lateral portion 26' of the slit 26 is spaced from the lower edge of the extension 22. In other words, the length of the slot 29 is substantially equal to the width of the flap 25 and is of a width slightly greater than the thickness of the flap so as to readily receive the flap 25 of an adjacent shingle therethrough. Furthermore, the slot 29 is spaced from the adjacent or forward end 21' of the recess 21 a distance substantially equal to the distance the hole or eyelet 27 is spaced from the end 13 so that when the holding flap 25 is properly received in the slot 29 of an adjacent shingle, the end 13 of the shingle having the flap substantially aligns with the adjacent

end 21' of the recess 21 adjacent the slot 29, as shown in Figures 2 and 3. Furthermore, the lower edge or side 12 of the upper shingle having the flap 25 registers with the lower edge or side 12 of the lower shingle having the slot 29, while the upper portion of the end 13 of the upper shingle aligns with the forward end 19' of the extension 19.

As illustrated in Figure 4, the shingles may be cut or blanked out of large sheets of material and, in order to effect economy, the extension 19 of each shingle is cut from the opposite side of another shingle, thus providing the edge 11 adjacent the end 14 with an extension 19, and the side 12 intermediate the ends thereof with a recess 21 complementary to said extension. The shingles are cut in pairs from a strip of sheet material with the shingles of each pair extending transversely of the sheet and with the ends 14 of the shingles at the center of the sheet complementary to each other, thereby eliminating waste of material. The stepped portions 16' of each shingle are spaced from the lower side 12 thereof a distance to provide the desired side lap with the next shingle and thus to determine the amount of head lap of one course upon the next preceding course.

As hereinbefore stated, my novel shingles are adapted to be laid in courses from the bottom or lower edge of the siding or roofing upwardly and those of each course are laid from the left-hand toward the right-hand side of the siding or roofing. As illustrated in Figure 2, the shingles of each course are laid with the longitudinal edge or side 12 lowermost, thus bringing the end 13 of each shingle in an exposed position at the left-hand side and the irregular and more or less angularly disposed end 14 of each shingle in a concealed position at the right-hand side of each course.

More specifically, when laying the shingles to form a roofing or siding construction, the lower left-hand shingle is first placed in operative position with its longitudinal edge 12 in alignment with the lower or bottom edge of the siding or roofing and with the end edge 13 aligned with the corresponding edge of the underlying supporting structure. A nail N is then driven through the shingle at the lower right-hand portion thereof, preferably between the forward end 21' of the recess 21 and the inner end portion of the slot 29, after which the opposite or left-hand end of the shingle may be secured to the underlying structure by driving a nail or other fastening means through the shingle at the upper left-hand corner thereof.

The next adjacent shingle in the same course is then brought into position by inserting its holding flap 25 through the slot 29 of the first shingle with the end 13 overlying the end 14 of the first shingle. If necessary, the second shingle is then swung about the flap 25 as a pivot to bring the edge 13 of the second shingle into alignment with the end surfaces 21' and 19' of the recess 21 and extension 19, respectively, of the first shingle. The second shingle is then secured in position by driving a nail N through the shingle intermediate the recessed end 21' and the slot 29 and another nail N' through the upper left-hand corner of the second shingle and through the upper right-hand portion of the first shingle defined by the curved surface 17, thereby securing both shingles to each other and to the supporting structure.

In like manner, each successive shingle of the

lower course is placed in operative position and secured to the underlying structure along the entire length of the siding or roofing. Before laying the shingles of the next or second course, a short shingle section 31 extending from a line connecting the inner ends 21" and 19" of the recess 21 and extension 19, respectively, to the end 14 is secured by nails or any other fastening means to the supporting structure in overlying relation with the first shingle of the first course in a manner which is well known to those skilled in the art to establish a beginning for the shingles of the second course. In positioning the shingle section 31, the amount of overlap of the shingles of the second course with the shingles of the first course is determined by aligning one of the steps 16' at the end 14, for instance the first step from the bottom or lower side 12, with the upper edge of the extension 19 of the first shingle of the first course.

The first or left-hand shingle of the second course may then be placed in operative position by inserting the holding flap 25 thereof into the slot 29 of the short shingle 31. Then, after aligning the end 13 of this first full length shingle of the second course with the end portions 21' and 19' of the recess 21 and extension 19 of the short shingle 31, and bringing the step 16' of the end 14 adjacent the lower edge of the shingle in alignment with the upper edge of the extension 19 of the second shingle of the first course, said first full length shingle is secured in position by driving the nail N through the portion of the second course lying between the recessed end 21' and the slot 29 and through the underlying portion of the second shingle of the first course into the supporting structure and then a nail N' is driven through the upper left-hand corner of the first full length shingle of the second course and the underlying portion of the shingle section 31 into the supporting structure.

The second full length shingle of the second course is then placed in position by first inserting the holding flap 25 through the slot 29 of the first full length shingle into interlocking engagement with the latter shingle, after which the second shingle may be properly aligned with the first shingle of the second course and with the third shingle of the first course, and then secured in position by nails N and N' in the manner hereinbefore described for the first shingle of the second course. In like manner, succeeding shingles of the second course are laid and secured in proper alignment with each other and in proper overlapping relation with the shingles of the first course, these operations for the several courses being continued throughout the length of the supporting structure.

It will now be observed that although I have illustrated but two nails or fastening means for each shingle, the structure as a whole is securely maintained in position to form a substantially water-tight covering. This is due to the fact that each shingle is secured to the underlying structure at least at three spaced places along its upper edge and at one place at its lower edge, the exposed lower corner of each shingle being secured to the underlying shingle by the flap 25. Furthermore, the interlocking engagement of the flap 25 of the upper shingle with the forward end portion of the adjacent lower shingle is so closely related with the fastening element N that said lower exposed corner of the shingles are se-

curely maintained against warping or being raised by the action of the wind.

In addition to the above, it will be noted that the lower side of each shingle rests upon and is supported by other shingles throughout the length thereof so that practically no vacant space appears beneath the lower edge of each shingle through which rain or water may be blown by the wind to a position above the upper edge of an underlying shingle of the next preceding course and thus cause leakage. This is due primarily to the fact that the extension 23 of each shingle of one course extends to substantially the end 13 of the next adjacent shingle of the preceding course, as clearly illustrated in Figure 3.

Furthermore, the extension 19 of each shingle is so arranged that when the shingles are laid in courses, these extensions align with the interlocked holding elements 25 and 29 of the shingles of the next succeeding course and maintain a practical uniform amount of overlap of the shingles of one course with the shingles of an adjacent course. At the same time, each course is provided with the irregular edge afforded by the recesses 21 and the desirable shadow line resulting therefrom. Also the curved end portions 17 and 17' provide the shingles with ample surfaces at the upper and lower sides thereof for fastening elements and for supporting the upper shingles and maintaining a closure thereunder. All of these features and the advantages derived therefrom are obtained by the use of a minimum amount of shingle material due to the peculiar manner in which the shingles are formed.

Although I have shown but two fastening nails N and N' for each shingle, it will be understood that additional fastening nails or elements may be used, if desired, for securing the shingles in position.

The modified form of shingle shown in Figure 5 is constructed substantially the same as that shown in Figure 1, with the exception of the end 14. This end of the shingle, instead of having the central portion as 33 thereof stepped, as at 16 in Figure 1, has this portion 33 extending in angular relation to the longitudinal center of the shingle and in tangential relation with the circular edge portions 17 and 17'. The end portion 33 may, as shown, be provided with notches 34 arranged in spaced relation longitudinally thereof to serve as guides in the same manner as the notches 16' of the shingle shown in Figure 1 for enabling the amount of overlap of the shingles of one course with the shingles of the next preceding course to be readily determined.

The shingle structure illustrated in Figures 6 and 7 is constructed substantially the same as that shown in Figure 1, with the exception that instead of providing the flap 25 and slot 29 for anchoring the lower exposed corner of each shingle with an adjacent shingle of the same course, the lower side of each shingle is provided with an incision or a slot 36 extending inwardly from the forward end 21' of the recess 21 for receiving an anchor clip 37 composed of metal or other suitable material and which is secured by any suitable means, as prongs 38 stamped up from said clip, to the end portion 13 of the shingle in slightly greater spaced relation to the lower side 12 thereof than that of the inner longitudinal edge of the recess 21. The shingles constructed in the manner shown in Figures 6 and 7 are laid in courses in the same manner as described above for the shingle shown in Figure

1, the lower exposed corner of each shingle being anchored to the adjacent lower shingle by insertion of the clip 37 in the incision 36, as indicated in Figure 7, it being understood that the clip has an offset portion 37' extending outwardly from the edge 13 of the shingle and spaced from the under side of the shingle to which it is secured a distance substantially equal to the thickness of the shingle so that when the clip is engaged in the incision 36 the extension 37' lies beneath the adjacent lower shingle, as illustrated in Figure 7, in a plane above the recess 21 of said latter shingle.

The modified form of shingle illustrated in Figure 8 is constructed substantially the same as the shingle shown in Figure 1, with the exception that the elements 25 and 29 are not formed in the lower edge of the shingle while the left-hand end, as 13', disposed at substantially right angles to the longitudinal edges 11 and 12 is of greater thickness than the remaining portion of the shingle. In this shingle the main portion thereof extending from substantially the plane of the end 21" of recess 21 to the end 14 is of usual thickness, that is, of substantially the same thickness as the shingle of Figure 1, while the remainder of the shingle, that portion 41 extending from the plane of the recess end 21" to the end 13', is of greater thickness than the remaining portion thereof so as to render the same stiff and of such rigidity that it will not be readily lifted by the wind when the shingles are laid in a roofing structure. This relatively thick rigid portion of the shingle eliminates the necessity of anchoring the lower exposed corner of the shingle with an adjacent shingle of the same course, as is necessary with the shingle shown in Figures 1 and 6. In the shingle shown in Figure 8, the end edge 13' is substantially twice the thickness of the shingle at the opposite end and the portion 41 gradually decreases in thickness from end 13' to substantially the line running crosswise of the shingle from end 21" of recess 21 to the end 19" of the extension 49 located at the upper edge 11 of the shingle. In other words, the portion 41 of the shingle is wedge-shaped, as indicated at 22', and although the end 13' is shown and described as having a thickness substantially twice that of the opposite end of the shingle, it will be understood that the thickness of the end 13' may be increased or decreased as desired.

These shingles are laid in courses in substantially the same manner as shown in Figure 2, with the exception of course that the lower exposed left-hand end of each shingle is not anchored by coacting locking elements, such as the holding flap 25 and slot 29 of the shingle shown in Figure 1, or clip 37 and incision 36 of the shingle shown in Figures 6 and 7. It will be observed that this relatively thick end portion 41 of each shingle not only provides a shingle which may be laid in a roofing structure without the use of anchoring elements provided at the lower exposed left-hand end of the shingle, but also provides a shingle wherein the shadow line of the lower edge thereof is substantially accentuated over that when the shingle is constructed in the manner indicated in Figures 1 and 6.

Although I have shown and particularly described a preferred form of shingle and modifications thereof, it is to be understood that these were for illustrative purposes only and that I do not wish to be limited to the exact construction shown as certain changes and modifications may

be made by those skilled in the art without departing from the spirit of the invention as set forth in the appended claims.

I claim:

1. A trapezoidal shingle of the character described adapted to be laid with one of the parallel sides thereof forming the lower edge of the shingle, said lower side of the shingle being provided with a recess arranged substantially midway between the ends thereof, the opposite or upper side of the shingle being provided with an extension complementary to said recess, one end of said shingle being straight and substantially normal to the longitudinal center line of the shingle and to said parallel sides, the portion of the shingle intermediate said straight end and the plane connecting the ends of said recess and extension adjacent said straight end of the shingle being of wedge shape in longitudinal section with the thickest portion or base thereof at said end of the shingle.

2. A surface covering comprising a plurality of flexible shingles of substantially trapezoidal form arranged in horizontal courses with the adjacent ends of the shingles of each course inlapping relation and with the adjacent lengthwise edges of the shingles of the several courses also arranged inlapping relation, each shingle being laid with one of the parallel sides thereof forming the lower edge of the shingle, said lower side of each shingle being provided with a recess extending inwardly from said edge and arranged intermediate the ends thereof, the opposite or upper side of each shingle being provided with an extension complementary to said recess, one end of each shingle being straight and substantially normal to said upper and lower parallel sides thereof, the portion of each shingle intermediate said straight end and the plane connecting the ends of said recess and extension adjacent said straight end being of greater thickness than the remaining portion of the shingle whereby said end portion of each shingle is relatively rigid with respect to said remaining portion thereof for the purpose set forth.

3. A surface covering comprising a plurality of flat flexible shingles of substantially trapezoidal form arranged in courses, each shingle being laid with one of the parallel sides thereof forming its lower edge, said lower edge of each shingle having two extensions, one extension adjacent either end thereof and a recess portion intermediate said extensions, interlocking means on each shingle comprising a slot in one of the extensions extending inwardly from the lower edge thereof in proximity to the end of the recess adjacent said latter extension, the other extension having an incision extending inwardly from the lower edge thereof and then outwardly away from the recess toward the adjacent end edge of the shingle to form an interlocking flap adapted to extend into the slot of an adjacent shingle of the same course, the spacings of the inner end of the incision from said end edge of the shingle and of the slot from said end of the recess adjacent thereto being substantially equal, whereby the said end edge of one shingle will be maintained substantially in alignment with the said end of the recess of an adjacent shingle of the same course when said shingles are locked to each other by the cooperation of the flap and slot.

4. A surface covering of the character defined in claim 3, wherein the upper side of each shingle is provided with an extension complementary to

the recess in the lower side thereof and the shingles of each course are laid with the ends of the recesses adjacent the flaps thereof substantially coincidental with said ends of the shingles of the next preceding course which are adjacent the flaps thereof, and wherein the lengths of the recess and of the extension having the interlocking flap of each shingle are substantially equal, whereby the interlocking connection provided by the flaps and slots of the shingles of one course lie in a plane intermediate

the ends of the corresponding extensions at the upper edge of the shingles of the preceding course to provide maximum protection against leakage.

5. A surface covering of the character defined in claim 3, wherein the lengths of the two extensions of each shingle are substantially equal, whereby the extension having the slot underlies the extension of an adjacent shingle of the same course having the interlocking flap substantially throughout the length thereof.

OTTO J. KUHN.
